UNITED STATES PATENT OFFICE.

MICHAEL MULCAHY, OF BAKERSFIELD, CALIFORNIA.

DESIGN FOR A HAT-PIN GUARD.

41,780.

Specification for Design.

Patented Sept. 19, 1911.

Application filed July 20, 1911. Serial No. 639,666. Term of patent 7 years.

To all whom it may concern:

Be it known that I, MICHAEL MULCAHY, a citizen of the United States, residing at Bakersfield, in the county of Kern and State of California, have invented a new, original, and ornamental Design for Hat-Pin Guards, of which the following is a specification, reference being had to the accompanying drawing, forming part thereof.

The figure is a perspective view of a hat pin guard, showing my new design.

I claim:

The ornamental design for a hat pin guard, as shown.

MICHAEL MULCAHY.

Witnesses:

MATTHEW S. PLATZ,
RICHARD POWERS.
